UNITED STATES PATENT OFFICE

GEORGE W. BACH, OF ERIE, PENNSYLVANIA, ASSIGNOR TO UNION IRON WORKS, OF ERIE, PENNSYLVANIA, A CORPORATION OF PENNSYLVANIA

WATER TUBE STEAM BOILER

Application filed March 18, 1929. Serial No. 347,776.

This invention relates to water tube steam boilers, and particularly to boilers for high temperature furnace conditions and high ratings required in present day installations.

5 The invention contemplates circulation of water to the lower drum for assuring proper water supply to the front element of the boiler to prevent rupture of the tubes of the front element or other damage should the baffle fail.

10 Also should the baffle fail and all the tubes then become upflow tubes, the water supplied to the lower front drum would therefore prevent overheating of these tubes and consequent rupture of the same.

15 An object of the invention is to provide a water tube steam boiler having large heating surface arranged to receive heat directly from the fire by radiation and with water circulation to the front heating element of the boiler.

20 Another object of the invention is to provide a water tube steam boiler having a large combustion chamber of A shape at the front of the boiler with a bank of tubes as a front element arranged to protect the front wall 25 from the furnace heat together with means for supplying water to the front element.

25 A further object of the invention is to provide a water tube steam boiler having a combustion chamber of A shape with a bank of tubes for the front element thereof in which element certain tubes are separated from certain other tubes by a baffle for creating a thermal siphon effect in the front element together with means for supplying water to the front element in case of failure of such baffle to thereby prevent rupture of the tubes which otherwise would occur due to overheating of the tubes.

30 A still further object of the invention is to improve water tube steam boiler construction by providing water supply to the front tubes thereof to prevent overheating of such tubes that might otherwise occur should certain parts of the boiler structure burn out in service.

35 A still further object of the invention is to provide water supply to boilers of the N type which will increase the efficiency of the same in use.

40 The above, other, and further objects of

the invention will be apparent from the following description, accompanying drawing, and appended claim.

According to the invention water is supplied to the lower front drum of the front 55 element or tubes so that in the event the baffle wall separating certain tubes of the front element fail then the water supply would prevent overheating of these tubes with consequent rupture of the same and also at the 60 same time assuring proper water supply for efficient operation of the boiler.

The form of boiler chosen to exemplify the invention is illustrated in connection with a boiler of the N shape type and it is to be understood that the invention is of course susceptible of use with boilers of other arrangement than that illustrated and described.

The illustrated boiler has an upper front 70 steam and water drum 1, an upper rear steam and water drum 2 which drums are connected by a bank of steam tubes 3 and a bank of water tubes 4. The drums 1 and 2 are parallel to each other and as illustrated are arranged transversely of the boiler setting.

75 A lower rear water drum 5 is arranged parallel to the drums 1 and 2. A front lower water drum 6 is suitably supported in the front wall 7 of the boiler setting.

The drums 1 and 5 are connected by banks 80 of tubes 8 and 9 which tubes may be curved or straight or partially curved and partially straight.

The lower front drum 6 and the upper front drum 1 are connected by banks of tubes 85 10 and 11 which tubes may be straight or curved or straight and curved. A baffle wall 12 is arranged between the tubes 10 and the tubes 11 of the two banks, the banks 10 and 11 constituting what is referred to herein as the front element of the boiler. The combustion chamber is A shaped being defined by the front element and also by the banks of tubes 8 and 9 connecting the drums 1 and 5.

90 The drums 2 and 5 are connected by a bank 95 of tubes 13 which may be of suitable arrangement and curvature to meet proper operating conditions.

100 A baffle wall 14 is arranged between certain of the tubes of the bank 9 which wall ex-

tends upwardly from the lower rear drum 5 towards the upper front drum 1 terminating in a substantially vertical wall or partition 15.

A wall 16 extends downwardly from the upper rear drum 2 towards and terminates short of the lower rear drum 5 with an angularly disposed wall 17 extending forwardly from the wall 16 towards the bank 9 of tubes and lying alongside of said bank for a certain distance. The zone or chamber included between the walls 14, 15, and 16 serves as a superheating zone or chamber wherein any suitable superheater may be installed if desired.

A lining 18 is arranged between the outer bank 10 of the tubes of the front element and the front wall 19 of the boiler structure. Likewise the steam tubes 3 are protected by a lining 20 while the lower front drum 6 is protected also by a continuation of the lining 18 downwardly and extending around this drum.

A water pipe 21 is connected between the lower drums 5 and 6 so as to supply water to the lower front drum 6 while the boiler is in use.

Tubes 22 are arranged at the rear of the furnace or combustion chamber A and communicate with the interior of the drum 5 at one end of said tubes while the other ends are secured to connections 23 from which extend upwardly pipes 24 which pipes enter the drum 5 so that heating of the water within the drum 5 may be accomplished by the heat from the furnace thus preliminarily heating the water supplied to the drum 5.

The furnace may be supplied with any type or kind of stoker or grates as desired and fired in any chosen manner. This feature forms no part of this invention and therefore it is not illustrated as it is well understood in boiler construction that any suitable or desirable type of grate or stoker may be employed in boilers of this character.

A plurality of hook plates 25 are provided for supporting hook blocks or similar lining structures within the boiler setting for obvious purposes.

The operation of the boiler as illustrated is as follows:

Water is supplied from any convenient source and fills the drums and tubes as indicated in the drawings. As the water is heated there will be a thermal siphon effect set up in the front element with circulation of the colder water downwardly through the tubes 10 and circulation of the hotter water or combination of water and steam upwardly through the tubes 11. The baffle wall 12 serves to keep the heat within the combustion chamber A from being dissipated through the front wall 19 of the furnace structure. The lower front drum 6 is supplied with water through the pipe 21 from the lower rear drum 5. Should the baffle 12 between

the tubes 10 and 11 of the front element fail for any reason then the circulation through the tubes 10 and 11 would be upwards or in other words these tubes would become up-flow tubes and the thermal siphon effect would be stopped the supply of water to the lower front drum 6 from the rear drum 5 would therefore prevent overheating of the tubes 10 and 11 as the water supplied to the front drum 6 would enter these tubes and thus become vaporized into steam and at the same time prevent overheating of the tubes because of the circulating of the water through the same.

The lower front drum 6 is supplied with water at all times from the lower rear drum 5 because of the pipe 21 connecting these drums. The front drum 6 is smaller in diameter than the rear drum 5 and is arranged in such relation to the vertical height of the rear drum 5 as to insure circulation from the drum 5 to the drum 6 at all times.

The provision of the baffle wall 12 results in a definite and rapid circulation of water on the tubes 10 and 11 creating the thermal siphon effect as the tubes 10 are protected by the baffle wall 12 from the heat of the gases in the combustion chamber A. The contents of the tubes 11 exposed to the gases of combustion consist of part water and part steam while the tubes 10 contain water thereby creating a rapid circulation in the direction indicated by the arrows. Furthermore, the provision of the baffle wall 12 protects the front wall 19 of the boiler from radiation losses so that the front wall may therefore be thinner than otherwise.

Circulation through the tubes 8 between the drums 1 and 5 will be upwardly that is from the drum 5 to the drum 1, whereas circulation in the tubes 9 will be downwardly as the tubes 8 are exposed to the gases of combustion more directly than are the tubes 9. The baffle wall 14 serves to deflect heat from certain of the tubes 9 for a part of the length of the same for increasing the efficiency of the circulation and thereby the efficiency of the boiler.

Whatever water there may be in the upper rear drum 2 that is cool passes downwardly through the tubes 13 to the lower rear drum 5 for reentering circulation.

The water in the drum 5 is preheated to a certain extent by circulation downwardly through the pipes 24 and upwardly through pipes 22. A blow off flange 25 is provided in the header 23 to eliminate sediment and the like.

The superheater zone or space B is substantially V shaped while the combustion chamber A is A shaped. This arrangement of the tubes makes possible operation of a boiler under high temperatures and with high ratings.

The water entering the tubes 8 and 11 from

the drums 5 and 6 respectively does not come in contact with any steam or water from the hotter parts of the boiler thus adding to the efficiency of the same. It will be observed also 5 that the boiler of this invention has a very large direct heating surface with a small amount of furnace wall subjected to the intense heat of the fire.

The baffle wall 12 is arranged transversely 10 of the boiler setting and is coextensive with the length of the tubes 10 and 11 of the front element, thus extending substantially the entire length of said bank of tubes and positioning certain of said tubes as 10 between the 15 baffle plate 12 and the front wall 19.

The invention has been described herein more or less precisely, yet it is to be understood that changes may be made in the arrangement and proportion of parts and that 20 equivalents may be substituted without departing from the spirit and scope of the invention.

The invention is claimed as follows:

A water tube boiler of the **N**-shaped type 25 having a furnace wall and a combustion chamber at the front end thereof, front and rear transverse steam and water drums, said pair of drums being connected to each other by an upper bank of steam tubes and a lower 30 bank of water tubes, a lower front water drum, a bank of tubes longitudinally positioned adjacent said wall connecting said water drum and said front water and steam drum, a baffle plate placed transversely between said tubes and extending longitudinally thereof substantially the entire length of said bank of tubes with a row of said tubes positioned between said baffle plate and wall, 35 a lower rear water drum of larger diameter than that of said front water drum, the bottoms of said drums being at substantially the same level, a bank of tubes connecting said lower rear water drum and said front water and steam drum to define with the tubes connecting said front water drum and said front water and steam drum an **A**-shaped furnace space, another bank of tubes connecting said lower rear water drum and said rear water and steam drum to define a **V**-shaped super- 40 heater space with a bank of tubes connecting the rear water drum and the front water and steam drum, the tube banks connecting the rear water drum and the steam and water drums having more tubes than the bank connecting the front water drum to the front steam and water drum, and a pipe connecting the bottom of the rear water drum and the bottom of the front water drum extending 45 substantially horizontal therebetween.

60 In testimony whereof I have hereunto subscribed my name at Erie, Erie County, Pa.
